(57) **CLAIM**

The ornamental design for a game board, as shown.

DESCRIPTION

FIGURE 1. FIGURE 1 consists of six panels, labeled 1 through 6, arranged in a 2x3 grid. Panel 1 is a scatter plot of $\log_{10}(M_{\text{gas}})$ versus $\log_{10}(M_{\text{star}})$. Panel 2 is a scatter plot of $\log_{10}(M_{\text{gas}})$ versus $\log_{10}(M_{\text{star}})$ with a linear regression line. Panel 3 is a scatter plot of $\log_{10}(M_{\text{gas}})$ versus $\log_{10}(M_{\text{star}})$ with a horizontal line at $\log_{10}(M_{\text{gas}}) = 10^9.5$. Panel 4 is a scatter plot of $\log_{10}(M_{\text{gas}})$ versus $\log_{10}(M_{\text{star}})$ with a horizontal line at $\log_{10}(M_{\text{gas}}) = 10^9.5$ and a vertical line at $\log_{10}(M_{\text{star}}) = 10^9.5$. Panel 5 is a scatter plot of $\log_{10}(M_{\text{gas}})$ versus $\log_{10}(M_{\text{star}})$ with a horizontal line at $\log_{10}(M_{\text{gas}}) = 10^9.5$ and a vertical line at $\log_{10}(M_{\text{star}}) = 10^9.5$. Panel 6 is a scatter plot of $\log_{10}(M_{\text{gas}})$ versus $\log_{10}(M_{\text{star}})$ with a horizontal line at $\log_{10}(M_{\text{gas}}) = 10^9.5$ and a vertical line at $\log_{10}(M_{\text{star}}) = 10^9.5$.

The sole FIGURE is a front view of a
